(57) **CLAIM**

The ornamental design for a self-venting microwaveable reclosable standup pouch, as shown and described.

DESCRIPTION

FIG. 1 is a perspective view of a self-venting microwaveable reclosable standup pouch showing my new design;
FIG. 2 is a front side elevational view thereof;
FIG. 3 is a rear side elevational view thereof;
FIG. 4 is a side elevational view thereof, the opposite side view being a mirror image thereof;
FIG. 5 is a top plan view thereof;
FIG. 6 is a bottom plan view thereof; and,
FIG. 7 is a front elevational view thereof, and showing the self-venting microwaveable reclosable standup pouch in an unfolded and flat condition.
